UNITED STATES PATENT OFFICE.

WILLIAM SEEHASE, OF HOLLAND, MICHIGAN.

ASH-CAN.

1,229,532.

Specification of Letters Patent. Patented June 12, 1917.

Application filed May 6, 1916. Serial No. 95,906.

To all whom it may concern:

Be it known that I, WILLIAM SEEHASE, a citizen of the United States, residing at Holland, in the county of Ottawa and State 5 of Michigan, have invented certain new and useful Improvements in Ash-Cans, of which the following is a specification.

My invention relates to improvements in ash cans, or receptacles for receiving and 10 removing ashes from furnaces, &c., and its objects are: first, to provide an ash can that may be so closely closed, when removing the can from the furnace to a place of deposit, that no dust can escape from it; second, to provide an ash can that may be so 15 connected with the furnace, or with the furnace chimney that all floating dust or ashes, raised by reason of shoveling ashes into the can will be immediately taken up and the 20 can will be immediately taken up and the danger of having the loose ashes fill the atmosphere in a furnace room, practically averted; third, to provide an ash can that 25 can be readily rolled away from the furnace room, up or down stairs, across a lawn, or otherwise handled without danger of scattering 30 ashes in the path of the moving can; fourth, to provide a bail for handling said can that may be readily connected with, or removed from the can and that, when removed from the can, the can may be made to stand firmly and steadily on end.

I attain these objects by the mechanism and construction shown in the accompanying drawings, in which Figure 1 is an elevation of the can as it appears when the bail is removed and the can is standing on end; Fig. 2 is a plan of the can as it appears when the bail is attached and the can is in position, and condition to be rolled away 35 from a furnace room; Fig. 3 shows the manner of connecting the can with a furnace, or a furnace chimney for the purpose of removing the floating dust or ashes when they are being shoveled from the furnace into the 40 can; Fig. 4 is a plan of the end of the bail that is to be connected with the bottom of the can; Fig. 5 is a plan of the end of the bail that is to be connected with the upper end, or cover of the can.

Similar numerals refer to similar parts throughout the several views in the drawing.

The can, 1, may be an ordinary ash can, but must be provided with outwardly extending pins, as 4, 4, arranged to be entered 55 into the slots or locking openings 5 in the cover 2, so the cover may be placed upon

the can, and by being turned around a trifle the pin will be passed into the opening 5 in such a manner as to draw the cover snugly against the end of the can, thus rendering the joint between the cover and can so close as to preclude the possibility of ashes, no matter how fine, passing out between them when the can is being rolled along over any suitable surface, as the 60 ground, a floor, or up or down steps. The cover 2 and the bottom 3 should be made to extend back well upon the body of the can 1, and should be considerably larger in their outer diameters than the can is so as to take 65 the weight of the can and its load and avert the danger, as far as possible, of the body of the can coming in contact with any object that may be in the line of movement of the can, and thus bending or marring 70 the can.

The lower end of the can is left perfectly flat and is provided with a hole in its center for the reception of the pintle 7, on the bail 8, for the purpose of averting the necessity 80 of placing an outwardly projecting pin, as that shown at 6 on the cover, thus leaving the bottom of the can in condition to stand firmly and squarely upon a floor, or other supporting surface. For the purpose of 85 averting the danger of fine ashes scattering out of the opening into which the pintle 7 is placed, I prefer to place a thickening element of some kind inside of the can, as indicated by the dotted lines 13 in Fig. 2, into 90 which the hole may be formed, or drilled.

The pintle, or pin 6, which is firmly connected with the cover 2 and projects outward therefrom, acts a double purpose: first, as a handle for manipulating the cover, 95 and, second, as a bearing to receive the hook, or loop 9 at the end of the bail 8, for the purpose of connecting the bail with the can to move, or roll the can along over the ground, &c., by pulling upon the bail 8. 100

To remove the bail from the can it is simply necessary to slide the end 9 back upon the pintle 6, as indicated by the dotted lines in Fig. 2, when this end of the bail may be carried off of the end of the can and the 105 pintle 7 may be readily removed from its bearing by sliding the bail, relatively to the left, and may be replaced by simply reversing the action.

In Fig. 3 I have shown the manner of 110 connecting the can with a furnace or chimney to prevent dust from floating from the

can when being shoveled into it. In this view 10 is a pipe that is designed to extend from the open top of the can 1, into the opening 12 in the chimney 11.

5 What I claim as new, and desire to secure by Letters Patent of the United States, is:—

10 1. In a dustless ash can, a cylindrical body, a bottom having a peripheral flange formed thereon to pass over the end of the body, said bottom having a small round opening in the radial center thereof, a cover having a flange turned thereon to pass down over the top of the can body, said flange having locking notches formed in opposite sides 15 of the cover, pins projecting from the body in position to be passed into said notches to lock the cover firmly onto the body, a pin projecting outward from the radial center of the cover, and a bail arranged so that one 20 end will pass into the hole in the bottom, and the other end may be looped over the pin on the cover.

25 2. In a dustless ash can, a cylindrical body, a bottom having the edges turned at right angles to form a flange around the end of the body, a hub projecting upward from the radial center of the bottom, the bottom and said hub having a central hole therein, a 30 cover having the edges turned at right angles to form a flange to extend downward

over the end of the can body and having notches therein, pins projecting outward from the upper end of the body to pass into the notches and engage the lips to hold the cover firmly upon the body, and a bail having a pintle formed on one end to enter the hole in the bottom of the can, and a loop formed on the other end of the bail, and a pin projecting from the radial center of the cover to enter said loop to so secure the bail 40 to the can that the can may be rolled thereby over any appropriate surface.

3. In combination with an ash can, a cover having a flange passed downward over the body of the can forming a hoop thereon, 45 means for locking the cover firmly upon the can, a pin projecting from the center of the cover, a bottom having a flange formed to extend upward over the body of the can, the center of the bottom thickened and having a 50 hole extending therein, a bail, a pintle formed at one end of the bail to enter the hole in the center of the bottom, a loop formed at the other end of the bail to engage the pin on the cover so the can may be readily rolled over suitable surfaces thereby.

Signed at Holland, Michigan, April 26, 1916.

WILLIAM SEEHASE.
